VENDING MACHINE

Harvey Giles, Brooklyn, N. Y., assignor to Collier Advertising Service, Inc., New York, N. Y., a corporation of Delaware

Application December 15, 1931
Serial No. 581,089

6 Claims. (Cl. 312—69)

This invention relates to an improvement in vending machines of the type in which an article is delivered to the purchaser when a coin of proper denomination is deposited in the machine 5 and a plunger or operating handle is manipulated.

One object of the invention is to provide in coin-controlled vending machines of the above described type, a simplified article delivery mechanism directly controlled by a coin of proper denomination held in a predetermined position to secure a more positive and reliable operation of the machine. Another object of the invention is to provide vending means so arranged and inter-related that the possibility of inserting 10 spurious coins or other articles into the machine for the purpose of surreptitiously obtaining the vended articles is prevented.

A still further object of the invention is to provide a simplified coin-operated means so arranged that the dispensing device is only operative on the insertion of a bona fide coin; and which prevents the retention of a coin when the machine is empty of merchandise, and which possesses numerous features of operation so desired 15 in machines of this character.

In the preferred embodiment of the invention illustrated in the accompanying drawings, Fig. 1 is a front elevation, partly in section, of my improved vending machine, with the cover plate 30 of the casing removed to disclose the operating mechanism; Fig. 2 is a sectional view on the line 2—2 of Fig. 1 looking in the direction of the arrows; Fig. 3 is a sectional view on the line 3—3 of Fig. 1 looking in the direction of the arrows; Fig. 4 is a sectional view similar to Fig. 3, illustrating how the cover plate acts to release the supporting plate of the hopper causing the same to be elevated, by the act of placing the cover plate on the machine casing; Fig. 5 is a sectional view on the line 5—5 of Fig. 1, looking in the direction of the arrows; Fig. 6 is a sectional view on the line 6—6 of Fig. 1, looking in the direction of the arrows; Fig. 7 is a longitudinal sectional view through the coin-operating mechanism, the view being taken on the line 7—7 of Fig. 8, looking in the direction of the arrows; Fig. 8 is a sectional view on the line 8—8 of Fig. 5, looking in the direction of the arrows; Fig. 9 is a sectional view on the line 9—9 of Fig. 5, looking in the direction 45 of the arrows; Figs. 10 and 11 are views similar to that of Fig. 9, illustrating the manner in which the plunger is freed for manual operation by the insertion of a suitable coin in the coin chute; Fig. 12 is a sectional view on the line 12—12 of Fig. 5, looking in the direction of the arrows; Fig. 13 is a sectional view on the line 13—13 of Fig. 5, looking in the direction of the arrows; Fig. 14 is a side elevation, with parts in section, of the upper end of the hopper, showing one of the 50 vended articles partially shifted from the stack

in the hopper and being directed into the merchandise chute; Fig. 15 is a view of the mechanism shown in Fig. 14, showing the vended article ejected from the stack and falling into the merchandise chute for delivery to the purchaser; Fig. 16 is a view of the mechanism shown in Figs. 14 and 15, showing the means for preventing operation of the delivery mechanism when the machine is empty of merchandise; Fig. 17 is a view of the mechanism shown in Figs. 14 to 16 inclusive, but taken at right angles thereto; Fig. 18 is a sectional view on the line 18—18 of Fig. 17, looking in the direction of the arrows; Fig. 19 is a sectional view through the ejector-plate, showing a part of one of the arms which support it, and Fig. 20 is a side elevation of the upper portion of the other arm which carries the ejector-plate, showing the means for restricting the swinging movement of said plate.

The mechanism forming the subject matter of this invention is contained within a suitable metal casing, the same being provided with a bottom 64, side walls 64a, a top 65a and a removable front plate or cover 76. At its lower end the front plate 76 is provided with a tongue 76a which enters into an aperture provided in an inturned flange 77a which is formed on the fixed lower portion 78a of the casing. The cover is locked in position on the casing in any of the ways common to vending machines.

The improved coin-controlled article delivery mechanism and the other improved devices associated therewith forming the subject matter of the present invention, are particularly adapted for use in connection with the vending of such relatively large and flat articles or packages as chocolate bars, peanut bars or other flat boxed or packaged merchandise, the stacked articles to be vended being shown at 25 in the drawings. These articles are supported in horizontal position in stacked relationship and are delivered to purchasers successively from the top of the stack. The lowermost article in the stack rests upon a supporting plate 26 of a hopper, said plate having downwardly bent ends 27 from each of which projects a stud 28. Each of these studs attaches to the end of a spring 29, these two springs acting to normally elevate the supporting plate 26 and the stack carried thereby, as fast as articles are removed from the stack by the delivery mechanism.

The fixed portion of the hopper comprises a frame mainly composed of four upright angle bars 30, 31, 32 and 33, which serve to vertically guide the articles in the stack. The lower ends of the two bars 30 and 31 are connected by a transverse plate 34, which has its end 35 bent at right angles and attached to a lower wall-plate 36, that is attached to the rear wall 38 of the casing, said plate 36 being held spaced from said

wall by spacers 38a. At their upper ends, the two bars 30 and 31 are connected by a transverse plate 39 which has its end 40 bent at right angles and attached to a plate 41 secured to the face of the rear wall 38 of the casing and held spaced therefrom by spacers 41a. It will be clear from the foregoing that the two bars 30 and 31, connected together at their opposite ends by the plates 34 and 39, form a side for the hopper. 10 Similarly, the two bars 32 and 33 are connected together and form the opposite side of the hopper. At their lower ends these bars 32 and 33 are connected by the plate 42 which has a laterally bent end 43 adjustably held on the lower wall plate 36 by bolts 44, which bolts extend through elongated slots 45 provided in the plate 36 to permit the two bars 32 and 33 to be shifted as a unit relative to the co-operating bars 30 and 31 to adjust the hopper for holding articles of 20 merchandise of different length.

At their upper ends the two bars 32 and 33 are connected by a plate 46 provided with a laterally bent end 47, through which bolts 48 pass to adjustably secure the plate 46 to the upper wall-plate 41 such connection being with slots provided in the wall plate 41 to permit shifting of the connected bars 32 and 33 to compensate for different length articles, as has been explained in relation to the lower portion of the bars 32 and 33. Thus, the two connected bars 32 and 33 may be shifted on their supports to enable the hopper to hold differently sized articles. Similarly, the bars 33 and 31 are capable of adjustment to or from their companion bars 32 and 30 respectively to compensate for packages or boxes of different width. To facilitate such adjustment, the lower plate 42 is provided with a slot 49 in which the securing-screw 50 may be held in any desired position of adjustment. A similar slot 51 is provided in the upper plate 46, which slot receives the screw 52 that attaches the bar 33 in position. The bar 31 is similarly adjustable to or from the bar 30 to regulate the size of the hopper frame. 45

The construction of the hopper will be clear, the same consisting primarily of the four upright angle bars 30, 31, 32 and 33, regulatable to varying sizes of packages, and the vertically movable supporting plate 26 on which the stacked merchandise 25 rests. As previously explained, this base plate is normally drawn upward by means of the springs 29 which extend from the studs 28 and pass over rollers 53, 54 provided on the plates 39 and 46 respectively, and thence extend to studs 55 and 56 projecting from the lower plates 34 and 42 respectively. Upward movement of the stack of articles 25 under the impulse of the springs 29 is restricted by the impingement of the uppermost article 25 in the stack against angular stop-plates 57 and 58 which are secured to the faces of the plates 46 and 39 respectively, and which overlie the articles in the stack adjacent their opposite ends as shown in Fig. 1. As fast as articles are removed from the stack, the stack is elevated under the impulse of the springs to always maintain the uppermost article in the stack against the stop-plates 57 and 58.

The delivery mechanism consists generally of a swinging or reciprocating frame having a pair of spaced parallel arms which carry an ejector-plate that acts to sweep the uppermost article in the stack from the stack and direct it into a delivery chute 78 carried by the cover plate 76. The two parallel arms just referred to are

indicated at 60 and 61. These two arms are so spaced that the hopper is located between them. The lower ends of these two arms are connected by a shaft 62, which is mounted to oscillate in bearings 63 which are secured to and extend upwardly from the bottom 64 of the casing. To permit the delivery frame to be easily removed, the shaft 62 is removably held in each of the bearings 63 by means of a locking plate 65 provided on each of the bearings, said locking plate being pivotally attached at 66 to enable it to be swung across the shaft 62 and then locked in such closed position by the thumb-screw 67. By loosening the thumb-nuts 68 and throwing back the locking plates 65 as indicated in dotted lines in Fig. 3, the shaft 62, carrying the arms 60 and 61 and their associated parts can be readily removed. 80

The upper ends of the arms 60 and 61 are connected by a cross-rod or brace 68 and also by an oscillating rod 69 that is held in slots 70 provided in each of the arms as shown in Figs. 19 and 20. Loosely mounted on the rod 69 is the ejector-plate 71, which is adapted, when the delivery frame is swung to the rear of the casing, to engage behind the uppermost article in the stack and, upon forward movement of the frame, slide the engaged article from the stack and into the delivery chute 78, as is disclosed in Figs. 14 and 15. The rocking movement of the ejector-plate 71 on its shaft 69 is restricted within certain limits by pins 72 which extend radially from the rod 69, and pass through slots 73 provided in that part of the plate 71 which surrounds the rod. 95

The connected arms 60 and 61 and associated parts, comprising the delivery frame, are normally held in their retracted position, shown in Figs. 2, 3 and 4, by means of a spring 74 having one of its ends attached to a stud 75 projecting from the arm 60 and its other end attached to the lower wall-plate 36. The delivery frame is drawn or rocked forward about its axis 62 by a manually pulled plunger that is freed for manual operation by the insertion of a coin in the coin-operating mechanism to be hereinafter described. 110

While in its retracted position the ejector-plate 71 enters behind the uppermost article 25 in the stack as shown in Fig. 3. On forward movement of the arms 60, 61, the ejector-plate, impinging against the rear edge of the article 25, slides it toward the front cover plate 76 of the casing where it is brought into contact with an inclined face formed on a deflector plate 77 attached to the inner face of the cover, which directs the ejected article downward into a delivery chute 78 carried on the inner face of the cover plate. The lower end of the chute 78 terminates in a tray 79 located on the outside of the cover plate, the ejected article passing through an opening 80 in the cover to reach the tray where it rests until picked up by the purchaser. On its movement toward the delivery chute the ejector-plate 71 is held almost vertical or in the position substantially as shown in Figs. 3, 4, 14 and 19, said plate being prevented from shifting with a pivotal movement to the right of Fig. 19, by reason of the fact that one end of each of the slots 73 is at the time abutting against the pins 72. A bodily rotative movement of the rod 69 on which the ejector-plate is mounted, is prevented by the fact that said rod is provided with a bent-down end 81, which, when the ejector-plate 71 is in its operative position shown in Fig. 19, abuts against a pin 82 projecting from the outer face of the arm 60. 125

The delivery mechanism consists generally of a swinging or reciprocating frame having a pair of spaced parallel arms which carry an ejector-plate that acts to sweep the uppermost article in the stack from the stack and direct it into a delivery chute 78 carried by the cover plate 76. The two parallel arms just referred to are

It will be clear from the foregoing that the ejector-plate 71 is held from pivotal movement on its operative movement which is had when the frame carrying said plate, swings toward the front 5 of the machine. The ejector-plate 71 on such movement bears against the rear edge of the uppermost article in the hopper and pushes it from the stack so that it falls into the chute as was heretofore explained. After the ejection of 10 the article, the springs 29 immediately elevate the stack and the next article in the stack strikes against the ejector-plate and swings it forwardly as disclosed in Fig. 15. The delivery frame is then 15 swung rearwardly under the pull of the retracting spring 74, and on such rearward movement the lower edge of the ejector-plate 71 slides smoothly across the upper face of the top article in the stack. To avoid injury to the wrapper on said 20 article, the lower end of the ejector-plate is provided with a surface 83 which slides smoothly over the top of the article 25 in the stack on the backward movement of the delivery frame. A bumper of rubber or of some similar substance is provided at 84 on the arm 60 to absorb the shock of 25 the return movement of the delivery frame, said bumper contacting with the face of the rear wall 38 of the casing and serving also to limit the extent of return movement of the frame. The forward swinging movement of the frame is limited 30 by shoulders 85a provided on the plates 39 and 46, the rod 69 being brought in contact therewith on the forward movement of the carriage. The coin-operated means for enabling the ejector-carriage to be manually swung forwardly to eject 35 the vended article upon the pull of a plunger, will now be described.

The coin-operated means is supported on a shelf or base plate 85 which has a downwardly extended rear end 86 that is slotted for the reception of 40 screws 87 which attach the shelf or base plate 85 to the lower wall-plate 36. The supporting shelf or base plate 85 is provided with a vertical wall 88 to which the coin chute 89 is attached by the screws 90.

Said coin chute 89 leads from a coin slot 91 provided in the front wall or cover 76 of the casing, and extends toward the rear of the casing at a slight downward incline, as clearly disclosed in 45 Fig. 6. The chute is divided, within the casing, into two channels or branches 92 and 93, the branch 93 forming a direct passage leading to a coin receptacle 94 supported upon a shelf 95, said coin receptacle being located directly beneath the outlet end 96 of the passage 93 so that coins passing therethrough will fall into the receptacle 94 in the conventional way. The branch or passage 92 of the coin chute is intended for the return of a coin that is inserted when the machine is empty of merchandise, or for the return of defective or 50 spurious coins or slugs which are sometimes inserted in these machines. This return passage 92 leads to an opening or slot 97 provided in the cover of the casing through which the returned coin passes to be received upon a holder 98 from 55 which it may be retrieved by the operator of the machine. A magnet 99 is provided at the junction of the coin chute branches so that it will attract iron slugs or the like and direct them into the return branch 92 from whence they will pass 60 out of the casing in the manner just explained.

At its rear end, the chute 90 is provided with an opening 100 through which the projecting end 101 of a coin deflector 107 enters into the chute. This deflector is pivoted at 102 and it is 65 normally adapted to be swung about this pivot

by the weight of a coin passing through the chute 89 and moving toward the branch 93 of said chute. Such a coin, striking the extended end 101 on the deflector 107 will swing the deflector about its axis 102 so that the end 101 80 located in the chute will be shifted out of the pathway of the descending coin and the coin will fall into the branch 93 and descend toward the lower end of the same, where it will be temporarily held as at 103 by the plunger-operated 85 mechanism to be hereafter described.

The coin deflector 107 is provided with a weight 104 to restore it to its normal position, which is illustrated in Fig. 6 after the passage of the coin. Under certain conditions, and particularly when the machine is empty of merchandise, or when the operation of vending an article is not fully completed, it is desirous of preventing the entry 90 of a second coin into the operating mechanism of the machine. That is to say, when the machine is empty or when the operating plunger has not completed its full action in causing the delivery of a vended article, coins then inserted 95 will be deflected through the return branch 92 of the coin chute and returned to the operator. This action is attained by means of a locking plate 105 pivotally mounted at 106 above the coin-deflector 107 and adapted under the conditions mentioned above to have its laterally-extended lower end 108 held against the edge of 105 the coin-deflector 107 to overcome the weight of a falling coin and to prevent said deflector from being swung out of the path of a coin entering through the chute, whereby said coin is shunted to the return branch 92 of the chute by the extended end 101 of the deflector. This "locked" 110 position of the locking member 105 is indicated in dotted lines in Fig. 6.

Under normal conditions, that is, when the delivery frame is in its retracted position and 115 ready for the next vending operation, the locking plate 105 is held in its elevated position, as shown in full lines in Fig. 6, so that the deflector 107 is free to permit the passage of a coin through the branch 93 of the coin chute. The locking 120 plate is held in such elevated position by means of a cam 109 provided on the face of the arm 60. The edge of this cam is brought into contact with a pin 110 projecting from the locking plate 105, so that while the arm is in its retracted position 125 and ready for its next article-ejecting action, the cam 109 prevents the locking plate 105 from acting on the deflector 107, said deflector being then inoperative for the purpose of deflecting an inserted coin into the return branch 92 of the coin 130 chute. On the other hand, when the arm 60 is moved forward to eject the vended article, it frees the locking plate which then acts upon the deflector, causing the same to deflect a coin into the return branch 92 of the coin chute, so 135 that a coin will not be retained by the machine until the vending operation then taking place is completed.

The plunger for swinging the delivery frame forward is shown at 111. It consists of a bar 140 having an end terminating in a handle portion 112 that projects through the cover plate 76 of the casing where it may be grasped and manually drawn outward to operate the delivery apparatus. Said plunger 111 moves along the upper 145 face of the shelf or base plate 85, its longitudinal movement relative thereto being restricted by means of a stud 113 located and movable within the limits of a slot 114 formed in the base plate 85. A spring 115 holds the plunger normally re- 150

tracted within the casing, said spring having one of its ends attached to a stud 116 which projects from a lug 117 formed on and projecting upwardly from the upper edge of the plunger. This 5 lug 117 also serves to swing the delivery carriage forward by being brought into contact with a projecting lug 167 attached to the arm 60. The plunger-retracting spring 115 extends over a roller 118 rotatably mounted upon the vertical 10 wall 88 of the base plate 85, and has its second end attached to a stud 119 also attached to the wall 88. To prevent the plunger from returning to its rearward normal position before completing its full forward movement, the lower edge 15 of the same is provided with the usual rack 120 located in a slot 121 provided in the base plate 85, said rack being engaged by the dog 122 held in its normal position by a spring 123, the lower end of which is connected to a pin 124 fixed in 20 a bracket 125 extending downwardly from the base plate 85.

When the parts of the machine are in their normal position, as shown in Figs. 1 to 4 inclusive, and ready for the vending operation, a coin 25 dropped into the chute 89 will swing the end 101 of the deflector 107 aside and will drop down into the branch 93 of the chute to a point adjacent the lower end 96 thereof where its descent will be stayed by the nose 126 of a plate 127, which 30 projects into the branch coin chute 93 through a slot 128 where it is held with sufficient resilient pressure to cause it to engage the coin 103 and hold it against further descent.

Said plate 127 is adjustably fixed to a lever 35 129 by a screw 130, the lever 129 being pivoted at 131 to a plate 133 attached to the base plate 85. At its end the lever 129 is provided with a vertical stud 132 which is operated upon a cam surface 134 provided on the face of the plunger 111. 40 Adjacent its inner end, the plunger is provided with a notch 135 adapted to be engaged by the nose 136 of a stop-lever 137 that is pivoted at 138 to the base plate 85. At its opposite end the lever 137 is provided with a laterally extending lug 139 45 which is directed toward the coin chute branch 93 and is adapted to bear against the face of the coin 103 lodged therein and held by the nose 126 and the plate 127. The stop-lever 137 is provided with a vertically-extending stud 140 which 50 enters into a slot 141 provided in the plate 127. A spring 142 bears against the stop-lever 137 adjacent its nose 136 and serves to direct the nose of the stop-lever 137 toward the notch 135 provided in the plunger. This spring 142 also 55 supplies the resilient pressure necessary to normally hold the nose 126 of the plate 127 directed into the coin chute branch 93.

In Fig. 9 the position of the parts just described is shown when no coin is in the chute. It will be 60 there seen that any effort to draw the plunger outwardly or toward the right of said figure, will result in the nose 136 of the stop-lever 137 becoming engaged with the notch 135 of the plunger 111 so that outward movement of the plunger 65 is prevented. When a coin is located in the chute portion 93 and is retained therein by engagement with the nose 126 of the plate 127, the plunger 111 can then be readily drawn out since the abutment of the lug 139 on the stop-lever 137 with the face of the coin, as shown in Fig. 10, prevents 70 pivotal movement of the stop-lever 137 under the impulse of its spring 142, which movement is necessary to cause the nose 136 thereon to engage with the plunger notch 135. As the plunger 111 75 is drawn out, its cam 134 is brought into contact

with the stud 132 which causes the lever 129 to swing about its pivot 131 withdrawing the nose 126 of the plate 127 out of the pathway of the coin 103 held thereby. The plate 127 on such movement, also pivots the stop-lever 137 through its pin-and-slot engagement therewith, so that the lateral lug 139 on said stop-lever 137 is moved from its contact with the face of the coin 103, whereupon the coin falls downwardly out of the coin chute branch 93 and into the coin receptacle 94.

The operation of the machine is briefly as follows:—The hopper is first filled with the vended articles 25 by drawing down the stack-supporting plate 26 until the same is located below the cut-away portion 143 of the front flanges on the front of the hopper upright bars 30 and 32. The stack-supporting plate is held in such lowered position by dogs 144 which are pivoted on the ends 27 of the plate 26 and which, when the plate 26 is lowered engage beneath the lower ends of the bars 30 and 32 as shown in Fig. 4. The plate 26 may be stacked with the articles to be vended by passing such articles through the space 143 and stacking them on the plate. When the hopper 100 is filled, the dogs 144 are manually released which permits the springs 29 to elevate the stack to bring the uppermost article 25 thereon into contact with the step plates 57 and 58 located at the upper end of the hopper. Should the person 105 filling the hopper fail to manually disengage the dogs from the ends of the bars 30 and 32, this operation will be automatically performed for him by the replacement of the cover plate 76 on the casing. Said cover plate 76 is provided with a 110 plate 145 projecting from its inner face, which, when the cover is replaced on the casing, contacts with the dogs 144 as shown in Fig. 4, causing the same to be swung inwardly and freed from their engagement with the ends of the bars 30 and 32 115 so that the stack is then carried upwardly under the impulse of the springs 29. When the cover is in place and suitably locked, the machine is then ready for operation.

A coin dropped into the chute 89 is directed 120 into the branch 93 as heretofore explained and descends to the position indicated at 103 in Figs. 6 and 10, where it is held by the nose 126. After 125 depositing the coin, the plunger 111 is then pulled. The plunger moves outwardly under the pull since the stop-lever 137 is rendered inoperative by the coin 103 located in the chute. As the plunger is drawn outwardly the lug 117 provided on the plunger, is brought into contact with the lug 167 on the arm 60 causing the delivery frame, 130 consisting of the connected arms 60 and 61 and associated parts, to be swung forwardly on its axis 62 toward the front of the casing. As the frame is swung forwardly, the ejector-plate 135 71 bearing against the rear edge of the uppermost article 25 in the stack, slides it from the top of the stack as shown in Fig. 14 toward the merchandise chute 78 into which it is directed by the deflecting plate 77 whereupon it terminates 140 its travel on the tray 79 from which it is picked up by the purchaser. When the pull is released on the plunger, it is retracted by the spring 115, while the delivery carriage is similarly retracted by its spring 74, and the machine is ready for 145 the next operation. The vending operation just described is repeated until the contents of the hopper are exhausted. When this occurs, a stop member 150 carried on the under face of stack-supporting plate 26 operates to lock the delivery carriage in a forward position (Figs. 16 and 17). 150

- The stop member 150 is pivoted at 151 in an ear 152 provided on the under face of the stack-supporting plate 26, and said member 150 is formed with an upwardly projecting finger 153 which a spring 154 tends to draw through an opening provided in the plate 26. When one or more of the articles 25 is resting on the plate 26, the weight of such article or articles is sufficient to maintain the stop member in its depressed position shown in Fig. 1. When there is no merchandise supported on the plate 26, the finger 153 on the member 150 is drawn upwardly by the spring 154 through the opening in the plate 26, so that the ejector-plate 71 on its released movement after having delivered the last article in the stack, impinges against the raised finger 153 and is prevented from returning to its fully retracted position, the delivery frame being thus held in a forward position as shown in Figs. 16 and 17. Consequently, since the arm 60 cannot return to its retracted position, the cam 109 thereon being out of contact with the locking plate 105, enabling said locking plate to function to prevent pivotal movement of the coin-deflector 107 so that the same acts to deflect coins thereafter inserted, to the return chute 92. This is continued until the machine is filled in the manner herein explained whereupon it is ready to fulfill its vending operations.
33. What I claim is:—
1. In a vending machine of the character described, a casing, a vertically disposed hopper located therein and having an open top, a vertically movable article support in the hopper, means for locking said support in a lowered position, a cover on the casing, means carried by said cover for releasing the locking means when the cover is fitted on the casing, a delivery frame surrounding the hopper, means for pivotally mounting said frame in the casing, a pivoted ejector-member mounted on said frame adjacent its upper end and above the open top of the hopper, means for causing said ejector-member to engage the uppermost article in the hopper on its movement in one direction to eject the article so engaged from the hopper, means for causing said ejector-member to freely return to its former position and there to engage the next article in the hopper, and a plunger for drawing the delivery frame in one direction.
  2. In a vending machine of the character described, a casing, a vertically disposed hopper located therein and having an open top, a vertically movable article support in the hopper, means for locking said support in a lowered position, a cover on the casing, means carried by said cover for releasing the locking means when the cover is fitted on the casing, a delivery frame provided with arms extending along the sides of the hopper and projecting above the top of the same, means for pivotally mounting said arms, an ejector-member carried by those parts of the arms which extend above the top of the hopper, means for causing said ejector-member to engage the uppermost article in the hopper on its movement in one direction and eject the article so engaged from the hopper, means for causing said ejector-member to freely return to its former position and there engage the next article in the hopper, means carried by the article-support for preventing the return movement of the ejector-member when the contents of the hopper have been depleted, and a plunger for drawing the delivery frame in one direction.
  3. In a vending machine of the character described, a casing, a vertically disposed hopper located therein and having an open top, a vertically movable article support in the hopper, means for locking said support in a lowered position, a cover for the casing, means carried by said cover for releasing the locking means when the cover is fitted on the casing, and means within the casing for successively ejecting articles from the open top of the hopper.
  4. In a vending machine of the character described, a casing, a vertically disposed hopper therein, a vertically movable article support constituting the base of the hopper, a catch member carried by said support, means within the casing adapted to be engaged by said catch member when the article support is in a lowered position to retain said article support in such position, a cover for the casing, a projection extending inwardly from the inner face of the cover adapted to disengage the catch member to permit of an elevating movement of the article support, and means within the casing for successively shifting articles from the support.
  5. In a vending machine of the character described, a casing provided with a bottom, a vertically disposed hopper within the casing, a delivery frame provided with arms extending along the sides of the hopper and projecting above the top of the same, an ejector member carried by those parts of the arms which extend above the top of the hopper, means for causing the ejector member to engage the uppermost article in the hopper on its movement in one direction and eject the article so engaged from the hopper, means for causing the ejector-member to return to its former position and there engage the next article in the hopper, a plunger for drawing the delivery frame through its ejecting movement, bearings on the base plate of the casing in which the delivery frame is mounted, means for holding the frame in said bearings, said means comprising a pivoted member adapted to be swung away from the bearings to permit release of the delivery frame therefrom, and facilitate the removal of the delivery frame and ejector member carried thereby from within the casing.
  6. In a vending machine, a vertically disposed hopper having an open top, a delivery frame provided with a pair of arms extending along the sides of the hopper and projecting above the open top thereof, a rod extending between the arms and pivotally mounted therein, an ejector member mounted to have a limited movement on said rod, a downwardly directed end on said rod, a projection extending from the face of one of the arms and located in back of the downwardly extending end of the rod and preventing backward pivotal movement of said end, plunger means for drawing the frame in one direction to cause the ejector member to move the uppermost article in the hopper out of the hopper, and means for returning the frame to a position with the ejector member in back of the next article in the hopper.

HARVEY GILES.
